UNITED STATES PATENT OFFICE.

MILLARD F. COX, OF LOUISVILLE, KENTUCKY, ASSIGNEE TO CAST STEEL PILOT COMPANY, OF ST. LOUIS, MISSOURI, A CORPORATION OF DELAWARE.

LOCOMOTIVE PILOT.

1,143,687.

Specification of Letters Patent. Patented June 22, 1915.

Application filed July 25, 1914. Serial No. 553,618.

To all whom it may concern:

Be it known that I, MILLARD F. Cox, a citizen of the United States, residing at the city of Louisville, county of Jefferson, State 5 of Kentucky, have invented a certain new and useful Improvement in Locomotive-Pilots, of which the following is a full, clear, and exact description, such as will enable others skilled in the art to which it 10 appertains to make and use the same, reference being had to the accompanying drawings, forming part of this specification, in which—

Figure 1 is a top plan view of a locomotive pilot of my improved construction. Fig. 2 is a front elevational view of the pilot. Fig. 3 is a side elevational view. Fig. 4 is a vertical section taken on the line 4—4 of Fig. 2. Fig. 5 is a view looking 20 against the underside of a pilot of my improved construction. Fig. 6 is a rear elevational view of the pilot.

My invention relates to new and useful improvements in pilots for locomotives, the 25 principal objects of my invention being to generally improve upon and simplify the construction of the types of pilots now in general use, and to provide a pilot, the main frame of which comprises two separately 30 formed skeleton members which are capable of being readily combined and applied to a pilot beam.

By forming the main frame or body of the pilot of two separately formed members, 35 the manufacture of the pilot is greatly facilitated and the cost of production is minimized.

Further objects of my invention are: to provide a pilot having slats which can be 40 readily detached and replaced in case of breakage; to form the upper portion of the pilot with a pocket or opening for the accommodation of the coupler and draw bar carried by the forward end of the locomotive; to form integral with the base of the 45 pilot plates which serve as steps to enable trainmen to mount the pilot and bumper beam, and further to provide a pilot which combines lightness of weight and simplicity 50 of construction with strength and rigidity.

With the foregoing and other objects in view, my invention consists in certain novel features of construction and arrangement of

parts, hereinafter more fully described and claimed.

As shown in the drawings, the lower or base member of my improved pilot is substantially triangular when viewed in a plane, and comprises a transversely disposed rear rail 10 with the ends of which are 60 formed integral the outer ends of a pair of inclined rails 11.

Formed integral with and connecting the intermediate portions of the rails 11 and arranged a short distance in front of the 65 rear rail 10 is an intermediate rail 12. All of the rails forming this triangular base are preferably L-shaped in cross section as shown, although it will be readily understood that said rails may vary in cross sectional shape as desired.

Formed integral with the ends of the rail 10 and the outer ends of rails 11 are horizontal steps for the trainmen when mounting or alighting from the pilot.

The upright frame which combines with the base comprises a pair of outer uprights or posts 14, a pair of inner uprights or posts 15, and horizontally disposed top rails or plates 16, the latter being formed integral with and connecting the respective pairs of uprights or posts.

The lower ends of all of the members 14 and 15 are provided with vertically disposed row of apertures 14^a and 15^a, the same serving as bolt or rivet holes, and by virtue of such construction the rear rail 10 of the triangular base can be positioned at different horizontal planes, thereby permitting vertical adjustment of the base member of the 90 pilot with respect to the vertical rear portion thereof and consequently permitting the production of pilots of different vertical dimensions.

Formed integral with and projecting outwardly from the outer end portions of the rails or plates 16 are horizontally disposed brackets 17 which bear directly against the underside of the pilot beam when the pilot is applied thereto.

The upper portions of the plates or rails 16 bear directly against the front face of the pilot beam and said rails or plates are provided with apertures which receive bolts or like devices utilized in attaching the pilot 105 to said pilot beam.

Formed integral with and projecting forwardly from the rails or plates 16 are horizontally disposed plates 18 which not only strengthen said rails or plates, but provide 5 points of attachment for the upper ends of the inclined slats forming a part of my improved pilot. These slats 19 are preferably sections of metal tubing cut to proper length and having their ends flattened in order 10 that they may be readily attached by means of rivets or like fastening devices to the flanges 18 and to the flanges on the rails 11.

By making these slats independent any one of them may be readily removed and 15 replaced in case of breakage.

Formed integral with and projecting forwardly from the inner posts or uprights 15 are forwardly projecting walls or plates 20, the same being extended upwardly at the 20 inner ends of the horizontally disposed rails or plates 16, and formed integral with and connecting the forward portions of these plates, but in a plane substantially below that occupied by the rails or plates 16, is a 25 horizontally disposed plate or rail 21 which serves as a point of attachment for the central series of slats 22. The lower forward corners of the vertically disposed walls or plates 20 are united by an integral trans- 30 versely disposed rail 23 which is riveted to the intermediate rail 12 of the base. It will be noted that this rail 23 is provided with vertical rows of rivet holes corresponding to the holes 14^a and 15^a, thereby permitting 35 the intermediate rail 12 to be attached to said rail 23 at different horizontal planes.

Formed integral with and connecting the central portions of the posts or uprights 15 is a transversely disposed rail 24, the same 40 occupying substantially the same horizontal plane with the rail 21.

The rectangular space A above the rails 21 and 24 and between the upper portions of the walls or plates 20 forms a pocket for the 45 accommodation of the draw bar and coupler carried by the forward end of the locomotive.

A pilot of my improved construction is 50 comparatively simple, can be easily and cheaply manufactured for the reason that the two main parts of the pilot can be readily cast and while said pilot is comparatively light in weight, it has the requisite strength and rigidity.

55 It will be readily understood that minor changes in the size, form and construction of the various parts of my improved pilot may be made and substituted for those herein shown and described, without departing 60 from the spirit of my invention, the scope of which is set forth in the appended claims.

I claim:

1. A locomotive pilot comprising a triangular base, a vertically disposed rear member, the lower portion of which is rigidly 65

fixed to the rear portion of the triangular base, there being a draw bar pocket formed in the upper portion of the vertical member, a pair of walls integral with the vertical member and projecting forwardly therefrom 70 at the sides of the draw bar pocket, and horizontally disposed rails connecting said walls at the lower end of said pocket.

2. A locomotive pilot comprising a triangular base, a vertically disposed rear member, the lower portion of which is rigidly fixed to the rear portion of the triangular base, there being a draw bar pocket formed in the upper portion of the vertical member, a pair of walls integral with the vertical member and projecting forwardly therefrom 75 at the sides of the draw bar pocket, horizontally disposed rails connecting said walls at the lower end of said pocket, and a series of separate slats arranged between the forward rails of the triangular base and the upper portion of the vertical member.

3. In a locomotive pilot, a base comprising a rear rail, a pair of inclined front rails, and a transversely disposed intermediate rail in front of the rear rail, a vertically disposed rear member, the lower end of which is fixed to the rear rail of the base, a pair of walls integral with and projecting forwardly from the vertically disposed member, the 90 lower portions of which walls are fixed to the intermediate rail of the base, and there being a draw bar pocket formed in the upper portion of the vertical member between the forwardly projecting walls 100 thereof.

4. In a locomotive pilot, a base comprising a rear rail, a pair of inclined front rails, and a transversely disposed intermediate rail in front of the rear rail, a vertically disposed 105 rear member, the lower end of which is fixed to the rear rail of the base, a pair of walls integral with and projecting forwardly from the vertically disposed member, the lower portions of which walls are fixed to the intermediate rail of the base, there being a draw bar pocket formed in the upper portion of the vertical member between the forwardly projecting walls thereof, and a series 110 of inclined slats between the inclined front rails of the base and the upper portion of the vertical member.

5. In a locomotive pilot, a base comprising a rear rail, a pair of inclined front rails, and a transversely disposed intermediate 115 rail in front of the rear rail, a vertically disposed rear member, the lower end of which is fixed to the rear rail of the base, a pair of walls integral with and projecting forwardly from the vertically disposed member, the 120 lower portion of which walls are fixed to the intermediate rail of the base, there being a draw bar pocket formed in the upper portion of the vertical member between the forwardly projecting walls thereof, a series of inclined 125

slats between the inclined front rails of the base and the upper portion of the vertical member, and brackets projecting rearwardly from the vertical member for engagement 5 with a pilot beam.

6. A locomotive pilot comprising a triangular base member formed in a single piece, a vertically disposed rear member which is formed in a single piece, means whereby the 10 base member can be attached to the vertical member at different horizontal planes so as to vary the vertical dimensions of the pilot, and a series of slats arranged between the front rails of the triangular base and the 15 upper portion of the vertical member.

7. In a locomotive pilot, a triangular base including a rear rail, a vertically disposed member including a series of uprights, the lower portions of which are provided with 20 vertically disposed rows of apertures adapted to receive attaching means, which latter means is seated in the rear rail of the base, and a series of inclined slats between the front portion of the base and the upper 25 portion of the vertical member.

8. In a locomotive pilot the combination with a triangular base composed of a rear rail, a pair of inclined front rails, and a transversely disposed intermediate rail, of 30 a separate vertically disposed rear member formed in a single piece, the lower portion

of which is adjustably connected to the rear and intermediate rails of the base member.

9. In a locomotive pilot the combination with a triangular base composed of a rear 35 wall, a pair of inclined front walls, and a transversely disposed intermediate rail, of a separate vertically disposed rear member formed in a single piece, the lower portion of which is adjustably connected to the rear 40 and intermediate rails of the base member, and there being a draw bar pocket formed in the upper portion of said rear member.

10. In a locomotive pilot the combination with a vertically disposed rear member 45 formed in a single piece and comprising a series of uprights and a pair of centrally arranged forwardly projecting walls, a transverse rail connecting the lower portions of 50 said walls, and a horizontally disposed skeleton base member adjustably connected to the lower portions of the uprights of the rear member and to the transverse rail at the lower ends of the forwardly projecting walls.

In testimony whereof I hereunto affix my signature in the presence of two witnesses, this 22nd day of July, 1914.

MILLARD F. COX.
